TRACK FOR TRACK LAYING WHEELS

Joseph Kuchar, Chicago, Ill., assignor to
Forged-Trak Co., Chicago, Ill., a Corpora-
tion of Delaware

Application May 21, 1932. Serial No. 612,663

5 Claims. (Cl. 305—10)

This invention relates to tracks for track laying wheels which are adapted to be laid on the ground so as to support a vehicle, and to be raised continuously as the vehicle proceeds.

5 The invention particularly relates to tracks for such wheels, comprising a series of articulated track elements, adjacent elements being adapted to interengage so as to provide a beam or bridge which is rigid against displacement in one direction and which is flexible with respect to displacement in the opposite direction.

One of the objects of the invention is to provide an improved track.

15 A further object of the invention is to provide an improved track element.

A further object of the invention is to provide an improved track and track element of the type described and claimed in my copending application, Serial No. 575,177, filed November 16, 1931.

20 A further object of the invention is to provide an improved track and track element which is simple in construction and economic to assemble and maintain.

25 Further objects, advantages and capabilities of the invention will hereinafter appear in the following description of a preferred embodiment thereof, taken in conjunction with the accompanying drawing, in which

30 Figure 1 is a plan view of a portion of the track, partly in section, taken on the line 1—1 of Fig. 2;

Fig. 2 is a side elevation of a portion of the track, partly in section, taken on the line 2—2 of Fig. 1;

35 Fig. 3 is a perspective view of one of the link elements, including a truss arm; and

Fig. 4 is a perspective view of the separate truss element.

40 Referring to the drawing, the improved track 10 is constituted by a number of articulated track elements 11, which are pivotally connected in series so that the same may accommodate themselves around supporting wheels in known manner. Means are provided upon each track ele-

45 ment so that they interlock in such a manner that the track is rigid when subjected to load in one direction, that is, the upward direction as viewed in Fig. 2, and is flexible and readily bent in the other direction. The rigidity referred to is im-

50 portant in the lower portion of the track in contact with the ground, this portion acting as an inverted bridge and taking the load applied by the vehicle supported by the track.

Each track element 11 comprises a shoe plate 12 which may be formed of forged steel, rolled

is provided with transverse grousers or ribs 13. At its forward and rearward edges the plate 12 is provided with complementary curved portions which cooperate with complementary elements upon the adjacent shoe plate in the manner shown in Fig. 2. On each side each shoe plate 12 has secured thereto a link element 14 which will now be described.

The link element 14 is preferably a forging of the structure and configuration shown in Figs. 1, 2, and particularly 3. The link element 14 is provided with bosses 15 and 16 which are staggered transversely in the longitudinal direction so that the outer face of the boss 15 is in substantial longitudinal alignment with the inner face of the boss 16, as will more readily be understood with reference to Fig. 1. The bosses 15 and 16 are connected by an oblique vertical web 17 which carries a lower web or base 18 and an upper web 19. The base 18 is provided on its upper side with bosses 20 which are provided with openings 21 whereby the link element may be secured to the shoe plate 12 by means of bolts 22. The upper surface of the web 19 is machined to provide a flat face 23. The flat faces 23 of the aligned link elements provide a track or rail for the passage of the wheels upon which the track is mounted, which track or rail is laid down in front of the wheels and is taken up after the last wheels have passed over it.

On the inner side of the surface 23 the link element is provided with an integral upwardly extending arm 24. In elevation this arm is preferably substantially triangular in shape, as will be seen from Fig. 2. The arm is preferably bent inwardly somewhat which will readily be understood from Figs. 1 and 3. At its apex each arm 24 is provided with a boss 25. This boss may suitably be located in vertical alignment with the boss 15 of the link element 14 which carries it, although it may be displaced forwardly or rearwardly from that position.

It will be understood that the link element 14, which is secured to the other side of the shoe plate 12, is exactly similar to that described, but is a mirror image thereof, so that the arms 24 and bosses 25 are located in transverse alignment. Each pair of arms 24 is connected by a pin 26 which has a drive fit in the bosses 25. The link element 14 is provided intermediate the bosses 15 and 16 with a boss 27, the inner face of which is in longitudinal alignment with the boss 15.

Each track element is provided with a truss ele- 110
ment 28, best shown in Fig. 4, which is located

between the link elements 14. The truss element 28 is preferably in substantially the form of an obtuse triangle, when viewed in elevation as in Fig. 2. At its base it is provided with 5 transverse openings 29 and 30 which are adapted to be placed in alignment with the bosses 15 and 27 of the link elements 14. The truss element 28 is secured in position by means of pins 31 and 32. The pins 31 have a drive fit in the bosses 27 and in the openings 30. The pins 32 extend through the bosses 16 of one track element, the bosses 15 of the adjacent track element, and through the opening 29 of the truss element 28 of the last said track element. Each pin 32 has 15 a drive fit in the bosses 16 and a working fit in the bosses 15 and in the opening 29 of the truss element 28. Consequently the pins 32 serve as pivots connecting adjacent track elements 11 and providing pivotal movement therebetween.

20 At its upper end the truss element 28 terminates in a head 33 provided with a concave face 34 which is of the same curvature as the pin 26 so that it is adapted to engage the pin 26 of the adjacent track element in the manner shown in Fig. 2. It will readily be understood, from this figure, that the reaction of the ground acting upwardly upon the shoe plates 12, forces the pins 26 into the recesses 34 of the heads 33 of the truss elements 28, and that this engagement results in 25 the trussing of the track so that it may effectively take the load and distribute the same over a large area.

The track is readily assembled, for example, in 30 the following manner. A pin 31 is forced into an opening 30 of a truss member 28 so that its end projects equally from either side thereof. A pin 32 is passed into the opening 29 and a pair of link elements 14 are presented to the truss element 28 with the bosses 15 and 27 in alignment 35 with the pins 32 and 31. A pin 26 is placed between the bosses 25 and in alignment therewith. The link elements 14 are then pressed inwardly by a suitable press until the bosses 15 and 27 contact with the truss element 28. A further 40 truss element 28, provided with pins 31 and 32, is then located with respect to the assembled portion of the track in the manner shown in Fig. 2, that is, with its head 33 in cooperative engagement 45 with the pin 26 of the assembled portion. A pair of link elements 14 are then pressed to the last 50 said truss element 28 so as to locate their bosses 15 and 27 in alignment with its pins 32 and 31, and with their bosses 16 in alignment with the pin 32 of the assembled portion of the track. The pin 26 is located in the appropriate 55 position with respect to the bosses 25 and the two last said links are pressed home.

This operation assembles a further portion of 60 the track and, in addition, pivotally secures the two assembled portions together, owing to the press fit which the bosses 16 have upon the pins 32. This operation is continued indefinitely until a track of the appropriate length is obtained. The link elements 14 may be secured to the shoe 65 plates 12 at any time after they are pressed into assembled position, that is, the shoe plates 12 may be installed progressively as each track element is assembled, or they may be installed after all other assembly operations have been completed.

In installing the track, it is merely necessary

to bring the bosses 15 of one extreme track element within and into alignment with the bosses 16 of the other extreme track element. A pin 32', slightly smaller than the pins 32, is then slipped through the aligned bosses and through the openings 29 in the truss element of the last said track element. The pin 32' may be held in position by suitable means, for example, cotter pins 35, which pass through openings in the ends 80 of the pin 32' and the bosses 16 at the ends thereof. 85

Although the invention has been described in connection with the specific details of a preferred embodiment thereof, it must be understood that such details are not intended to be limitative of the invention except in so far as set forth in the accompanying claims. 90

I claim:

1. A track comprising a plurality of track elements pivotally connected together in series, each track element comprising a shoe, a pair of link elements bolted thereto, each of said link elements being provided with an integral truss arm, and a truss element secured to said link elements and adapted to cooperate with the truss arms of 100 an adjacent track element. 95

2. A track comprising a plurality of track elements pivotally connected together in series, each track element comprising a shoe, a pair of link elements bolted thereto, each of said link elements being provided with an integral truss arm, transverse means connecting said truss arms at an elevated point, and a truss element secured to said link elements adapted to cooperate with the transverse means of an adjacent track element. 105

3. A track comprising a plurality of track elements pivotally connected together in series, each track element comprising a shoe, a pair of link elements bolted thereto, each of said link elements being provided with an integral truss arm, a pin having a press fit in each opposed pair of truss arms at an elevated point thereof, and a truss element pinned between said link elements, 115 the first said pin being adapted to engage the truss element of the next track element. 120

4. A track comprising a plurality of track elements pivotally connected together in series, each track element comprising a shoe, a pair of link elements bolted thereto, each of said link elements being provided with an integral truss arm, a pin having a press fit in said truss arms at an elevated position thereof, and a truss element extending transversely between said link elements and rigidly pinned thereto, said truss element being adapted to engage the first said pin of the next track element. 125

5. A track comprising a series of track elements each track element comprising a shoe, a pair of link elements bolted thereto, each link element carrying an integral truss arm, a truss element between said link elements, pins having a press fit in the link elements of one track element and a working fit in the link elements of an adjacent track element connecting said elements in series in pivotal relation, said pins extending through said truss element, and pins having a press fit in said link elements and in said truss elements, said pins rigidly securing said truss elements on said track elements. 135 140 145
